UNITED STATES PATENT OFFICE.

JACQUES SCHLUMPF, OF OBERWINTERTHUR, SWITZERLAND.

APPARATUS FOR TREATING VEGETABLE, ANIMAL, OR ARTIFICIAL FIBERS WITH DYES OR OTHER LIQUIDS.

Application filed March 24, 1926; Serial No. 96,972, and in Great Britain March 14, 1925.

This invention relates to dyeing machines of the circulation kind, and particularly to machines of the type in which the dye is caused to circulate in a direction which can be reversed at will by the operation of a suitable valve. This invention has for its object an improved machine of this type in which the quantity of dye flowing in the upward direction can be moderated at will with a view to preventing the fibers under treatment from becoming entangled.

According to this invention I provide two chambers adapted to receive the goods to be treated, said chambers being connected to the circuit of a circulating pump through a reversing valve adapted to enable the direction of flow to be reversed at will in both chambers, and being provided with a single by-pass allowing the rate of upward flow of the dye in the chambers to be moderated at will.

Referring to the drawings filed which illustrate as an example a particular arrangement of a dyeing machine made according to this invention:

Fig. 1 shows diagrammatically a plan of the circulating arrangement;

Fig. 2 shows diagrammatically an elevation of the same;

Fig. 3 shows the internal arrangement of the two chambers, with racks adapted to hold the skein supporting-rod;

In Figs. 1 and 2, a_1 and a_2 are the two chambers, b is the pump causing the circulation of the dye in the system, c is a four-way valve by means of which the circulating dye can be sent to and pumped from a_1 and a_2 respectively, or its direction of flow reversed. h is a by-pass by way of which a quantity of liquid, regulated by the cock k , can pass either into the chamber a_1 by the branch pipe m_1 , or in the chamber a_1 , by the branch pipe m_2 , according to the position of the four-way valve c , as explained hereafter. In the position shown, the liquid is sent by the pump b into the piping f through the valve c and the connection e_2 , into the lower part of the chamber a_2 , in which it rises and passes into the chamber a_1 , by the two branches m_1 , m_2 of the by-pass, proceeds in a downward direction into the chamber a_1 and thence, by the connection e_1 , the valve c and the piping g , it returns to the pump b . Now, with a normal rate of flow of the liquid upwardly in the chamber a_2 , the skeins

would depart from their vertically hanging position owing to the upward thrust of the flowing liquid, and would become entangled. The cock k is therefore opened and adjusted so that a certain proportion of the liquid delivered by the pump can pass in the bypass h , the amount passing through the piping f , being just sufficient to lift the silk slightly and so prevent any possibility of stick-marking, without in any way disturbing the condition of the hanks. In the chamber a_1 , where the liquid is flowing downwardly, the rate of flow may be increased without inconvenience, and this is obtained by the liquid flowing along the bypass h , passing into the chamber a_1 by means of the branch m_1 . In other words, there are two liquor circuits in the apparatus, namely $b f c a_2 m_2 m_1 a_1 c g b$, and $b k h m_1 a_1 c g b$, these two circuits being coincident along m_1 $a_1 c g b$, so that on this latter portion of the circuit, a proportionately larger rate of flow of the dye is obtained, according to the amount of opening of the cock k . On operating the valve c , the direction of flow is reversed the two circuits being now in coincidence along the portion $m_1 a_2 c g b$ of the circuit, with a large downward rate of flow through the chamber a_2 , while there is a reduced rate of flow upwards in the chamber a_1 .

In Fig. 3, a_1 and a_2 are the two chambers as before, separated by a passage corresponding to h , and communicating by means of an aperture m with passages m_1 and m_2 corresponding to the branches of the by-pass of Figs. 1 and 2. Racks n are provided on the walls of the chambers to receive the supporting rods p for the skeins q . The two chambers communicate with the passage h by openings e_1 , e_2 controlled by a reversing valve (not shown).

The chambers a_1 , a_2 and the passage h are closed by a panel provided with packings ensuring a tight joint, under the pressure of a suitable toggle or other device, in the known manner.

It will be understood that, although the arrangement described comprises only one pair of chambers, any convenient number of such pairs of chambers can be connected to the circulating system, a single by-pass being used for the whole system.

The invention has been described in respect of dyeing but is clearly applicable to

any case in which it is required to treat fibers or other materials with a circulating liquid, for other purposes besides dyeing.

I am aware that it has been proposed, in 5 apparatus of the type described, to provide each chamber with a by-pass and a regulating valve, whereby the amount of liquid passing in either direction may be regulated, and I do not claim such an arrangement.

10 What I wish to secure by U. S. Letters Patent is:—

A dyeing machine of the type described,

comprising a circulating pump, a circulating pipe system, two chambers adapted to receive the goods to be treated, said chambers being connected to the circuit of said circulating pump, a reversing valve adapted to enable the direction of flow to be reversed at will in both chambers, and the system being provided with a single by-pass allowing the rate of flow of the dye in whichever chamber the flow is upwards to be moderated at will.

15 In witness whereof I affix my signature.

JACQUES SCHLUMPF
